UNITED STATES PATENT OFFICE.

GUNNAR O. LILJEGREN, OF ST. LOUIS, MISSOURI.

AUTOMATIC FIRE-EXTINGUISHER.

1,176,380.

Specification of Letters Patent. Patented Mar. 21, 1916.

Application filed November 4, 1915. Serial No. 59,528.

To all whom it may concern:

Be it known that I, GUNNAR O. LILJEGREN, a citizen of the United States, residing in the city of St. Louis and State of Missouri, have invented a new and useful 5 Automatic Fire-Extinguisher, of which the following is a specification.

This invention has reference to automatic fire extinguishers.

10 The object of the invention is to provide an improved link for use in connection with angular strut levers of an automatic fire extinguisher, and consists essentially of a number of plates adapted to engage with the 15 levers and separated or spaced by balls seated in suitable depressions or recesses formed for their reception in the plates, said plates also being provided with suitable flanges adapted to engage and hold the solder 20 whereby the plates are united.

In the accompanying drawings in which I have illustrated one embodiment of the invention, Figure 1 is a side elevation of an automatic fire extinguisher nozzle equipped 25 with my present invention. Fig. 2 is a sectional view. Figs. 3 and 4 are perspective views of the two plates comprising the links separated from each other.

30 The nozzle 1 is provided with the usual yoke 2 and with a closure 3. The yoke supports an adjustable screw 4 in axial alignment with the nozzle and angular levers 5 for the ends of their strut-forming arms bearing against the closure and the screw, so 35 that by holding said levers in proper position the closure will be retained against the nozzle.

My present invention comprises a novel 40 form of link for engaging and holding the levers together.

The link comprises two plates of duplicate construction, of which the plate 6 is the upper plate and the plate 7 is the lower plate. Each plate is provided with an extension 8 having a hole therethrough adapted to receive the end of the corresponding lever 5 as will be understood by reference to Figs. 1 and 2. Each plate is also provided with two arcuate flanges 9 at the sides of the 45 extensions 8 and the flanges 9 of each plate extend across the end of the adjacent plate when the two are assembled in the form of the complete link. Each plate is further provided with two laterally extending arms 50 10 adjacent to and below the flanges 9, said arms 10 being formed on the side edges of

the plates. Thus the upper plate 6 is formed with the flanges 9 and the arms 10 adjacent to its upper end and the lower plate 7 is formed with similar flanges 9 and arms 10 adjacent to its lower end, so that the lower portion of the upper plate rests between the arms 10 on the lower plate, and the upper portion of the lower plate rests between the arms 10 on the upper plate. Each of said 60 plates is pressed or swaged to form concave recesses 11 in its inner face, and in the specific embodiment shown there are four of such recesses in each plate, though it will be understood that the number may be varied 70 as desired.

The recesses in the two plates are arranged opposite each other and are adapted to receive the balls 12 which seat within the recesses in the two plates and constitute 75 ball bearings for holding the plates apart and to facilitate their separation when the solder becomes fused under the influence of heat. The balls 12 are of such size that they hold the plates out of contact with each 80 other so that there is an intervening space in which a quantity of solder 13 is placed for the purpose of assisting in holding the plates together in the form of a continuous link. Solder 14 is also placed in engagement with the flanges 9 and the end of the adjacent link, thus positively retaining the 85 two plates together. Since the solder 14 positively prevents lateral movement of the two plates away from each other, it is obvious that there can be no relative longitudinal movement of the plates for the reason that the balls 12 are seated in opposing recesses 11 and constitute positive locking elements to prevent relative longitudinal movement of either plate with respect to the other until the solder 14 becomes broken or fused. However, when the solder 14 is broken or fused longitudinal movement or 90 separation of the two plates under the influence of the pressure of water within the nozzle exerted upon the levers 5, is facilitated. As a result of this construction the balls 12 not only serve as locking elements 95 to prevent relative longitudinal movement of the two plates when the solder is in position, but they also serve as ball bearings to facilitate such longitudinal movement when the solder becomes fused, thus securing the separation of the link members under the 100 pressure exerted by the water.

The use of a number of the balls 12 suit-

ably spaced to provide proper bearings for the plates and locking connections at different points serves different functional purposes than can be attained by the use of rollers or other similar elongated locking members, since the balls being spherical are capable of movement in every direction and do not become wedged or locked and prevent separation of the link plates after the solder has fused.

10 What I claim and desire to secure by Letters Patent of the United States, is—

15 1. In an automatic fire extinguisher, a link comprising two duplicate plates, each of which is provided with an extension at one end, flanges on each plate at the sides of said extension, a plurality of concaved recesses formed in the inner surface of each of said plates near the upper and lower ends

20 thereof, said recesses being oppositely disposed, spherical bodies placed in said recesses and holding said plates equally spaced from end to end, and solder interposed between the ends of said plates and said flanges preventing spreading of said plates.

25 2. In an automatic fire extinguisher, a link for holding the strut levers in position comprising two duplicate plates having extensions on their upper and lower ends respectively, said extensions having holes for the purpose described, flanges integral with each plate at the sides of said extension, a plurality of concaved recesses formed in the inner surface of each of said plates near the upper and lower ends thereof, said recesses in the two plates being opposite each other, spherical bodies placed in said matching recesses holding said plates equally spaced from end to end, and solder interposed between the ends of said plates respectively and said flanges preventing said plates from separating.

3. In an automatic fire extinguisher, a link of the character described comprising two duplicate plates, each of which has an extension on one end provided with an opening, flanges integral with each plate at the sides of said extension, solder between said flanges and the adjacent end of the other plate, a plurality of concaved recesses in the inner surface of each of said plates, the recesses in each of said plates matching and being opposite the recesses in the other plates, spherical bodies placed in said recesses holding said plates equally spaced from end to end, arms on the side edges of each plate extending across the side edges of the adjacent plate, and solder placed between said flanges and the adjacent side edges of the other plate holding said plates from relative lateral movement.

4. In an automatic fire extinguisher, a link for the purpose mentioned comprising two duplicate plates each having an extension at one end, flanges at the sides of said extension extending below the plane of the end of the adjacent plate, a plurality of concaved recesses formed in the inner surface of each of the plates, spherical bodies placed in said recesses and holding said plates equally spaced from end to end, arms on each plate embracing the side edges of the other plate, and solder placed between said flanges and the end of the adjacent plate to prevent relative lateral movement of said plates.

In witness whereof, I have signed this specification in the presence of two subscribing witnesses.

GUNNAR O. LILJEGREN.
